CLAIM

The ornamental design for a pocket device with knob member design, as shown and described.

DESCRIPTION

The present invention is a design for a product enabling secure product transport.

FIG. 1 is a front view of one embodiment of the present invention.

FIG. 2 is a top view of the embodiment shown in FIG. 1.

FIG. 3 is a right side view of the embodiment shown in FIG. 1.

FIG. 4 is a rear view of the embodiment shown in FIG. 1; and,

FIG. 5 is a bottom view of the embodiment shown in FIG. 1.

Items shown in phantom are for illustrative purposes only and do not constitute a part of the claimed design.
